UNITED STATES PATENT OFFICE.

JEREMIAH J. DELANY, OF NEW YORK, N. Y.

FAUCET.

SPECIFICATION forming part of Letters Patent No. 759,246, dated May 10, 1904.

Application filed May 31, 1902. Serial No. 109,812. (No model.)

To all whom it may concern:

Be it known that I, JEREMIAH J. DELANY, a citizen of the United States, residing at New York, in the county of New York and State 5 of New York, have invented new and useful Improvements in Faucets, of which the following is a specification.

My invention relates to spigots for wash-basins; and the object of the same is to construct a device of this character attachable to either hot or cold water pipes and which shall be simple in construction and efficient in operation.

The novel construction of my device is fully 15 described in this specification, and claimed and illustrated in the accompanying drawings, forming a part thereof, in which—

Figure 1 is a vertical longitudinal section of my device in its normal closed or shut-off 20 position. Fig. 2 is a horizontal section on the line *a a*, Fig. 1. Fig. 3 is a detail section and elevation of the valve. Fig. 4 is a detail of the cam.

Like characters of reference designate like 25 parts in the different views of the drawings.

The numeral 1 designates a casing inclosing the movable parts of my spigot. The casing 1 is provided with a base 2 of ordinary form, adapted to be secured to the top of a wash- 30 stand. (Not shown.) The casing is traversed by longitudinally-extending recesses 3 and 4 and a transverse recess 6. A diagonal passage 5 connects the recesses 4 and 6 and an aperture 7 establishes communication between 35 the lower ends of 3 and 6.

Connected to the recess 4 is a service-pipe A, shown in fragment. A valve is mounted within the transverse recess 6 and comprises a stem B, having a head C keyed thereon and 40 a coiled spring L surrounding the stem B and bearing at its inner end on the head C. A cap N, fitted on the casing, bears against the outer end of the spring L and serves to confine it. The head C fits tightly the recess 6; 45 but grooves C' therein permit the passage of water. The inner end B' of the stem B is rounded off for a purpose which will appear and this rounded end extends through the reduced aperture 7 and into the recess 3. A 50 gasket D is fitted over the stem B and slotted

on the inner face of the head C, and thus forms a valve which normally fits over the aperture 7 and prevents the passage of water.

Means for operating the valve to permit the flow of water when desired is supplied by 55 a rounded cam G, carried by a hollow spindle E, closed at its lower end, but perforated in the side at F. The spindle E loosely fits the recess 3, but is held centered by a trunnion 8, fitting a reduced portion 9 of the recess 3. A 60 rim M, integral with the spindle E, limits its upward movement. Caps I and J, fitting snugly the spindle E, hold it securely and provide means for holding packing to prevent all leakage. The upper end of the spindle E 65 is pierced by a perforation H and a hollow gooseneck O is tightly fitted over the spindle with its bore in register with the perforation H. A plug K, having a rim K' thereon, closes the upper end of the spindle and holds the 70 gooseneck O in place. By this arrangement water can flow from the spindle into the gooseneck O.

When in use, my device is mounted adjacent to a basin with the gooseneck O directed 75 toward the basin when the cam G is engaging the stem B. The water will then flow from the pipe A through recess 4, passage 5, recess 6, the grooves C', spindle E, gooseneck O, and into the basin. To shut off the water, it 80 is only necessary to turn the neck O about one-fourth of a revolution in either direction, when the cam G will release the stem and permit the spring L to seat the gasket over the aperture.

I do not wish to be limited as to details of construction, as these may be modified in many particulars without departing from the spirit of my invention.

Having described my invention, what I 90 claim as new, and desire to secure by Letters Patent, is—

In a device of the character described, a casing having separate longitudinal passages, one of said passages having a lateral extension or 95 arm communicating with a corresponding extension of the upper one of said longitudinal passages, a spring-pressed valve arranged and seated in the latter extension of said casing and having its stem suitably extending 100.

into one of said longitudinal passages, said valve also having a marginally notched or slotted head, the notches or slots permitting the flow of the water by or past said head, a 5 tubular spindle arranged in said upper longitudinal passage, and having a cam adapted to engage and actuate said valve as said spindle is turned, and a gooseneck, or outlet-pipe, connected to, and communicating with, said 10 spindle and adapted to provide for turning

the last named, said spindle being stepped or bearing in the bottom of said upper longitudinal passage.

In testimony whereof I have hereunto set my hand in presence of two subscribing witnesses. 15

JEREMIAH J. DELANY.
